CLAIM

The ornamental design for a display screen with transitional graphical user interface of a billiard game, as shown and described.

DESCRIPTION

FIG. 1 is a front view of the first image of a display screen with transitional graphical user interface of a billiard game play showing our new design in accordance to a first embodiment;

FIG. 2 is a front view of the second image thereof following the image shown in FIG. 1;

FIG. 3 is a front view of the third image thereof following the image shown in FIG. 2;

FIG. 4 is a front view of the second image thereof following the image shown in FIG. 1 in accordance to a second embodiment;

FIG. 5 is a front view of the third image thereof following the image shown in FIG. 4 in accordance to a second embodiment;

FIG. 6 is a front view of the second image thereof following the image shown in FIG. 1 in accordance to a third embodiment;

FIG. 7 is a front view of the third image thereof following the image shown in FIG. 6 in accordance to a third embodiment;

FIG. 8 is a front view of the second image thereof following the image shown in FIG. 1 in accordance to a fourth embodiment; and,

FIG. 9 is a front view of the third image thereof following the image shown in FIG. 8 in accordance to a fourth embodiment.

The dash-dot broken line showing a display screen and even broken line showing portions of the graphical user interface of a billiard game do not form part of the claimed design. The appearance of the transitional image sequentially transitions between the images shown in FIGS. 1-3 in the first embodiment, FIGS. 4-6 in the second embodiment, and FIGS. 7-9 in the third embodiment. The process or period in which one image transitions to another image forms no part of the claimed design.
